DESIGN FOR AN HOMOGENIZER OR SIMILAR ARTICLE

Pierce M. Travis, Ridgewood, and Michael K.
Tudor, Clifton, N. J.

Application September 19, 1947, Serial No. 141,486

Term of patent 14 years

(Cl. D23—1)

To all whom it may concern:

Be it known that we, Pierce M. Travis, a citizen of the United States and a resident of Ridgewood, in the county of Bergen and State of New Jersey, and Michael K. Tudor, a citizen of the United States and a resident of Clifton, in the county of Passaic and State of New Jersey, have invented a new, original, and ornamental Design for an Homogenizer or Similar Article, of which the following is a specification, reference being had to the accompanying drawings, forming part thereof, and in which

Fig. 1 is a perspective view from the front of an homogenizer, showing our new design,

Fig. 2 is a side elevational view thereof, and

Fig. 3 is a top plan view thereof.

We claim:

The ornamental design for an homogenizer or similar article, substantially as shown.

PIERCE M. TRAVIS.
MICHAEL K. TUDOR.
